DESIGN FOR A BURIAL VAULT OR SIMILAR ARTICLE

George Dalton Myers, Cincinnati, Ohio, assignor
to The Edwards Manufacturing Company,
Cincinnati, Ohio, a corporation of Ohio

Application February 11, 1935, Serial No. 55,330

Term of patent 7 years

To all whom it may concern:

Be it known that I, George Dalton Myers, a citizen of the United States of America, residing at Cincinnati in the county of Hamilton, State of Ohio, have invented a new, original, and ornamental Design for a Burial Vault or Similar Article, of which the following is a specification, reference being had to the accompanying drawing, forming part thereof.

The figure is a perspective view of a burial vault

or similar article, showing my new design, in which the essential features reside in the article shown in full lines, the handles being illustrated in broken lines.

I claim:

The ornamental design for a burial vault or similar article as shown and described.

GEORGE DALTON MYERS.
